UNITED STATES PATENT OFFICE.

FREDERICK A. DILLINGHAM, OF TROY, OHIO, ASSIGNEE TO THE TROY CARRIAGE SUN
SHADE COMPANY, OF TROY, OHIO, A CORPORATION OF OHIO.

WIND-SHIELD.

1,255,394.

Specification of Letters Patent. Patented Feb. 5, 1918.

Application filed November 8, 1915. Serial No. 33,339.

To all whom it may concern:

Be it known that I, FREDERICK A. DILLINGHAM, a citizen of the United States, and a resident of the city of Troy, in the county of Miami and State of Ohio, have invented certain new and useful Improvements in Wind-Shields, of which the following is a full, clear, and exact description, reference being had to the accompanying

10 drawing, forming part of this specification.

My invention relates to wind shields for closed bodies in automobiles and the like. The customary practice in closed bodies of mounting wind shields therein is a difficult 15 and tedious operation. In the aperture left in the body it is necessary to set a wind shield of the proper size and to leave no gaps between it and the sides of the opening of the body. Accordingly pivot members 20 are customarily mortised into the sides of the aperture in the body, and this is hand work which must be done accurately; or else the shield will not be placed cleanly and accurately in the opening of the body. 25 The plate on which the pivot member is mounted must be so mortised in place that it is flush with the sides of the body opening and the pivot members must not extend out too far, or else the shield will be 30 held away from the body at the sides, so considerable care must be taken in this work.

In cheaper constructions, pivot members are mounted on the outside of the body opening, and in such case there is nothing 35 to guide the mechanic in properly placing his pivot members, so that it takes considerable time and effort to obtain this proper position. Not only this, but pivot members so mounted are liable to jar loose and cause 40 considerable annoyance by their rattling.

In shields which have an upper and a lower pivoted member, the work of installation is merely doubled in difficulty, and in addition proper spacing of the upper and 45 lower pivots must be provided for.

Accordingly it is the object of my invention to provide a wind shield in which the mounting thereof at the sides of a closed body is taken care of by a fitting which 50 screws direct on the sides of the body opening, so that all that is necessary for the manufacturer of the automobile to do is to provide an opening of the proper size in the body, and secure the mounting members of 55 my shield along the inside of this opening,

whereupon the shield may be set into its place without further adjustment.

It is further the object to provide an auxiliary shield to extend down in front of the main upper shield, said former shield and 60 the main shield simply and adequately protected from rain blowing over the top of them into the inside of the car by an improved wiping device.

These objects and various other advantages I accomplish by that certain construction and arrangement of parts to be herein-after more specifically pointed out and claimed.

In the drawing,

Figure 1 is a front elevation of the shield taken from the inside of an automobile.

Fig. 2 is a section taken on the line 2, 2, of Fig. 1.

Fig. 3 is a section taken on the line 3, 3, of Fig. 1.

Fig. 4 is a cross section taken just above the pivot points, looking down on the two upper shield members.

Fig. 5 is a perspective view of a corner of one of the upper shields.

Fig. 6 is a perspective view of the left hand side frame member.

1, 1, are the sides, and 2 and 3 the top and bottom of the opening left in a closed body 85 for the wind shield. Into this opening are set the side pieces 4, 4, which are provided in the proper size specified by the car builder, and are to be screwed in place along the side 1 by suitable screws 5, 5.

The side pieces are formed with a channel 6, slightly to one side of their center line and in this channel are set the flexible strips 7, 7, which will wipe the sides of the pivoted wind shield sections.

Near the top of the side pieces are formed split collars 8, 8, for the main and auxiliary wind shield sections respectively, and near the bottom are formed the split collars 10 for the lower wind shield section. It will 100 be understood that these pivot collars are integral with the side pieces and accordingly no thicker than the main frame portions of said pieces, so that the inside edges of the pivot collars are exactly flush with the 105 frame within which the wind shield is to swing.

The collars each have a pin 11 passing through the split ends, to which pin is secured the clamping finger 12. This finger 110

has a cam upper edge 13, which loosens or tightens the collars with the movement of the fingers so as to free the shield section for movement and clamp them in any desired position.

14 is the main upper shield section, 15 the auxiliary section and 16 the lower section. Each section has proper pivot studs 17 which fit within the split collars. The shields are made up with any desired form of molding, but it is preferred to have a hollow metal molding 18, with a channel 19 for the glass portion of said shields.

Mounted along the top 2 of the opening 15 in the body is a plate 20 having channel members 20^a for retaining a wiping strip 21 for the main upper section of the shield. The plate has a forward extension in the shape of an angling flange 22, which has 20 on its outer surface the channel forming members 23 for a wiping strip 24 for the auxiliary shield section.

The lower shield section molding has a wiping strip 25 mounted on its lower surface 25 which wipes a plate 26 mounted over the bottom 3 of the body opening.

It is now plain that a wind shield completely protected on all sides by wipers is provided. The wipers for the two upper sections are not always in contact with their tops, but whenever the sections are swung outwardly, the wiper for the auxiliary section will be in contact position, and when the shields are vertical the other wiper will 35 be in contact. By this means unsightly curved members for maintaining constant contact are done away with.

It is also plain that the two side pieces which form the frame in which the shields 40 are pivoted, may be secured in place without any fitting, and greatly simplify the work of installing the shield sections. The shield portions are made to size and the opening in the body may be easily made 45 accurately to size, so that when it comes to assembling, all that need be done is to screw in the sides, with the shield sections already in place in their proper sockets.

It is not desired to limit the claims that 50 follow by failure to mention equivalent structures during the course of the above description.

Having thus described my invention, what I claim as new and desire to secure by Letters Patent, is:—

1. In a device of the character described, in combination with the front frame of a closed car body provided with an opening therein for the reception of a wind shield, 60 side members adapted to be rigidly secured

within said opening against the inner side faces of said frame and extending to the top and bottom of the frame, said members provided with pivoting devices thereon for the shield.

2. In a device of the character described, in combination with the front frame of a closed car body provided with an opening therein for the reception of a wind shield, side members adapted to be rigidly secured 70 within said opening against the inner side faces of said frame and extending to the top and bottom of the frame, said members provided with pivoting devices thereon for the shield flush with the inner faces of said side members.

3. In a device of the character described, in combination with the front frame of a closed car body provided with an opening therein for the reception of a wind shield, 80 side members adapted to be rigidly secured within said opening against the inner side faces of said frame and extending to the top and bottom of the frame, said members provided with pivoting devices thereon integral therewith and flush with the inner faces of said side members.

4. In a device of the character described, in combination with the front frame of a closed car body provided with an opening 90 therein for the reception of a wind shield, side members adapted to be rigidly secured within said opening against the inner side faces of said frame and extending to the top and bottom of the frame, said members 95 provided with pivoting devices thereon for the shield, and with a wiping strip inserted longitudinally therein the length thereof to close the opening between the shield and side members.

5. In a device of the character described, in combination with the front frame of a closed car body provided with an opening therein for the reception of a wind shield, side members adapted to be rigidly secured 105 within said opening along the sides thereof and extending the length of the sides of the shield, said members provided with split collars formed integral therewith to form pivots and sockets for the wind shield.

6. In a device of the character described, mounting means for a wind shield in the opening of a closed car body, comprising side members to be secured against the sides of said opening and extending the length 115 of the sides of the shield, said members having upper and lower split collars formed integral therewith for an upper and a lower wind shield section.

FREDERICK A. DILLINGHAM.
